UNITED STATES PATENT OFFICE

HAYMOND A. ALLTOP, OF FAIRMONT, WEST VIRGINIA, ASSIGNOR OF ONE-HALF TO
ORA M. DOOLITTLE, OF FAIRMONT, WEST VIRGINIA

WHEEL-LIFTING DEVICE

Application filed April 8, 1926. Serial No. 100,761.

This invention relates to wheel lifting devices.

An important object of the invention is to provide a device of simple construction adapted for lifting car or other wheels from boring mills and the like after the boring action has been completed.

A further object is to provide a device having a substantially cylindrical body portion adapted to be inserted through the axle opening in a wheel and provided with engaging members adapted to project outwardly from the body portion to engage the lower side of the wheel to permit it to be lifted.

A further object is to provide means for withdrawing the engaging members when it is desired to release the device from the wheel.

20 A further object is to provide a substantially integral body having engaging members pivotally mounted in recesses therein for engaging the lower side of a wheel to permit it to be lifted, the device being provided with means adapted to be engaged by a hook or the like carried by a crane whereby the lifting operation may be performed.

Other objects and advantages of the invention will become apparent during the course of the following description.

In the drawings I have shown one embodiment of the invention. In this showing:

Figure 1 is a perspective view of the device,

Figure 2 is a central vertical sectional view,

Figure 3 is a bottom plan view, and,

Figure 4 is a section on line 4-4 of Figure 2.

Referring to the drawings the numeral 10 designates a preferably integral substantially cylindrical body formed of suitable material and provided on opposite sides with slots 11, the inner faces 12 of which converge toward the bottom of the body. The body is provided with a pair of spaced upstanding ears 13, as clearly shown in Figures 1 and 2, and a bolt 14 passes through these ears above the upper end of the body. Referring to Figure 2, the numeral 15 designates a pair of fingers having their inner ends pivotally connected within the slots 11 by means of transverse

pivot pins 16. These fingers are adapted to extend outwardly a substantial distance beyond the body when they are in operative position, as shown in solid lines in Figure 2, and each finger is provided with a bevelled portion 17. As previously stated the fingers are pivotally mounted within the body and are adapted to be swung upwardly to inoperative position as indicated by dotted lines in Figure 2. The body is provided with a pair of converging openings 18 communicating with an angularly arranged opening 19 formed in the body, as shown in Figures 1 and 2. Each finger 15 is provided with an eye or similar element 20 to which is connected the lower end of a flexible operating member 21 preferably formed of rawhide or the like. The operating members 21 are connected to a common operating member 23 formed of the same material and provided at its upper end with a finger engaging loop 24.

The slots 11 may be formed in the body portion by milling or the like and the lower ends of the slots are closed by a plate 25 which is preferably circular and of the same diameter as the body 10. The plate 25 is secured to the lower face of the body by screws 26, or cast solid to main body. The plate 25 is provided with openings 27 communicating with the slots 11 for a purpose to be described.

The operation of the device is as follows:

The vehicle wheel or the like is placed on a machine such as a boring mill and after the boring or other operations have been completed, it is desired to lift the wheel therefrom. Vehicle wheels are of course very heavy and difficult to lift from position. With the present device the lifting operation is very much simplified and the wheel readily may be lifted from position. In operation, the device is inserted through the axle opening by inserting it from the upper side of the wheel, the fingers 15 freely moving upwardly, as will be apparent. The body portion is preferably of nearly the same diameter as the axle opening whereby it fits therein. The device is inserted in the manner described until the free ends of the fingers 15 are per-

mitted to drop to horizontal position, as indicated in solid lines in Figure 2. The bolt 14 is adapted to be received in a hook or the like suspended from a crane. Operation of the crane to move the device upwardly obviously will bring the upper faces of the fingers 15 into engagement with the lower face of the wheel whereby the latter may be elevated. As previously stated the body portion is of substantially the same diameter as the axle opening whereby the fingers 15 will be properly centered and the wheel will be balanced. When it is desired to release the device from the wheel, the crane is lowered permitting the device to slip downwardly a sufficient distance to permit the fingers 15 to swing free of the wheel. Upward movement of the outer ends of the fingers is accomplished merely by lifting the operating member 23 whereby the fingers will swing to the dotted line position shown in Figure 2, and the device may be readily withdrawn from the wheel. It will be noted that the inner ends of the fingers 15 are spaced from the inner walls 12 of the slots 11. With the openings 27 arranged to communicate with the inner and lower portions of the slots, it will be apparent that any dirt, metal chips or other foreign matter finding its way into the slots will pass out through the openings 27 and thus will not interfere with the proper operation of the fingers.

It is to be understood that the form of the invention herewith shown and described is to be taken as a preferred example of the same and that various changes in the shape, size and arrangement of parts may be resorted to without departing from the spirit of the invention or the scope of the subjoined claim.

Having described my invention, I claim:

A device of the character described comprising a vertical integral cylindrical body provided in opposite sides with vertical slots 46 extending from the top to the bottom thereof, the inner faces of said slots converging toward their lower ends, and with upwardly converging openings communicating at their lower ends with said slots, said body being further provided with an opening extending from the top thereof and communicating at its lower end with the upper ends of said first named openings, a finger provided with a hub engaging face and pivotally connected at its inner end to said body in the lower portion of each of said slots, said fingers being adapted to swing to substantially horizontal positions with their lower ends projecting beyond said body, a plate secured 60 against the lower end of said body and adapted to contact with said fingers when the latter are in operative position, an eye carried by the hub engaging face of each of said fingers and within said slots, flexible means connected to said eyes for swinging said fingers

upwardly to inoperative positions wholly within said slots, said flexible means extending upwardly through said openings and having an upper end arranged above said body, said body having a pair of parallel integral projecting members extending upwardly beyond its upper end and arranged transversely with respect to said slots, said projecting members being provided with alined openings, and a bolt extending through 70 said alined openings.

In testimony whereof I affix my signature.
HAYMOND A. ALLTOP.
